UNITED STATES PATENT OFFICE.

CARL P. NACHOD, OF PHILADELPHIA, PENNSYLVANIA, ASSIGNOR TO NACHOD SIGNAL COMPANY, INC., A CORPORATION OF NEW YORK.

ELECTRIC SIGNALING SYSTEM.

1,158,143.

Specification of Letters Patent. Patented Oct. 26, 1915.

Application filed October 13, 1908. Serial No. 457,520.

To all whom it may concern:

Be it known that I, CARL P. NACHOD, a citizen of the United States, residing in the city of Philadelphia, county of Philadelphia, 5 and State of Pennsylvania, have invented a new and useful Electric Signaling System, of which the following is a specification.

My invention relates to a system of signaling to be used in connection with car or 10 train movements of railways, and particularly to the car or train movements of a railway system using electrical energy for its motive power, and particularly to such electric railways as have single track sections or blocks with turnouts at various intervals for the passage of cars moving in opposite directions, or to such railways as are for the major part double tracked, and have one or more single track sections.

20 In general, my invention relates to such a system as disclosed in U. S. Patent No. 825,927 granted to me on July 17, 1906.

My present invention resides in the circuit arrangements and controls, in a system 25 as above described, and further in the signaling apparatus as employed in and with such a system, such circuits and controls and apparatus being hereinafter described and claimed.

30 For an illustration of one of the forms my invention may take, reference is to be had to the accompanying drawing, in which:

Figure 1 is a diagrammatic view of the 35 signaling system circuits and controls in normal condition, that is, with no signal displayed. Fig. 2 is a front elevational view, parts in section, of the signaling apparatus. Fig. 3 is a side elevational view, partly in section, of the no voltage control apparatus.

40 Fig. 4 is a detailed view of a portion of the no voltage control apparatus. Fig. 5 is a detailed view of the parts shown in Fig. 4, but at right angles thereto. Fig. 6 is a top plan view, partly in section of the ratchet wheel 45 circuit controller.

Referring to Fig. 1, 1 represents the trolley or contact feeder wire or conductor of an electric railway system for a single track block or section which is of considerable 50 length, but here shown as relatively short. At either end of the block or section 1 are turnouts or side tracks to allow cars going in opposite directions to pass each other, or double tracked sections, there being a sig-

nal station A at the turnout or double track 55 at the left and a similar signal station B at the turnout or double track at the right, the trolley or contact conductor being branched at station A into the double track or turnout or branch conductors 2 and 3, 60 while at station B the single track conductor 1 branches into the double track or turnout or branch conductors 4 and 5.

The turnout conductors 2 and 4 are concerned with traffic toward the left, while the 65 conductors 3 and 5 are concerned with traffic toward the right, as indicated by the arrows.

Assuming a car or train to be passing from the turnout or station A to the block or section 1, the trolley or other means for engaging the contact conductor or trolley conductor will put the trolley switch contact 6 into communication with the conductor 3 for a short interval of time thus allowing current to pass from the conductor 3 through 75 the contact 6, conductor 7, brush or contact 8, contact ring 9, brush or contact 10, conductor 11, thence through the winding 12 of the solenoid or electro-magnet C, thence through conductor 13, contact or brush 14, 80 contact 15, carried by and insulated from the movable core or armature of the solenoid or magnet C, thence through contact or brush 16, thence through resistance 17, conductors 18 and 19 to earth or the return 85 track or conductor 20 of the electric railway system. After the movable armature or core of the electro-magnet or solenoid C has moved some distance, the brushes 14 and 16 separate from the contact 15, thus throwing the additional section of resistance 21^a 90 into the circuit of the winding 12. By this arrangement, when the solenoid or magnet C is first energized a more powerful current flows through its winding than after it has begun to act, when a less powerful current suffices to complete the movement and hold the parts in shifted position. The energization of the magnet or solenoid C serves to

rotate the contact wheel 21 one notch (by 100 mechanism hereinafter described) causing the block of insulation 22 on the wheel 21 to be rotated from under the brush 23, so that the brush 23 engages the metallic wheel 21 with which there is a continuous contact 105 made by the brush 24. The movement of the armature or core of the magnet C toward the right, when the magnet C is energized,

besides stepping the wheel 21 around one notch, pushes, by means hereinafter described, the movable armature or core of the magnet D toward the right, and then, 5 later, the magnet D is energized, as will be described, and holds its armature or core in the attracted position toward the right. And the movable member of the magnet or solenoid C carries an insulated conducting 10 pin 45 with which normally engage the contacts or brushes 46 and 47. And the movable member of the magnet or solenoid D carries a similar insulated conducting pin 48 with which are adapted to engage the 15 brushes or contacts 49 and 50.

When the magnet C is energized and its armature or core moves to the right, contact is broken between the brushes 46 and 47 and the pin 45 and established between the 20 brushes 49 and 50 and the pin 48, due to the fact, as above mentioned, that the movable member of the magnet or solenoid C pushes the movable member of the magnet D to the right at the same time that 25 the wheel 21 is stepped around a notch. The contact between brush 23 and the wheel 21, occurring as above described, allows current to pass from the contact conductor or trolley wire 3 through the conductor 25 and 30 the winding 26 of the electro-magnet or solenoid D, thence through conductor 27, brush 23, wheel 21, brush 24, conductor 28, brush or contact 29, through contact ring 30, brush or contact 31, conductor 32 through 35 the closed hand switch 33 thence through the signal wire 34, which extends between the two stations A and B, thence through the closed hand switch 33 at station B, conductor 32, brush 31, contact ring 30, brush 40 29, conductor 28, brush 24, contact wheel 21, thence through the conducting pin 35 carried by and in electrical communication with the wheel 21, thence through the contacting brush 36, conductor 37, thence through the 45 winding 38 of the electro-magnet or solenoid E, thence through conductor 39 through brush 40, contact ring 41, brush 42, conductor 19 to earth or return conductor 20, current flowing also through the red electric 50 lamp R, through conductors 43 and 44, such lamp being in parallel with the winding 38 of the electro-magnet or solenoid E. This energization of the magnet or solenoid D, at station A, causes its armature or core, 55 previously pushed over by the energization of the magnet C, to be retained in attracted position against the opposition of a spring hereinafter referred to. And this energization of the magnet D causes or allows the 60 white semaphore at station A to be displayed, and the white electric light W, at station A, to burn because of current coming from the contact conductor or trolley wire 3 through conductor 51, the lamp W, conductor 52, brush 49, contact pin 48 (which

has been brought under the brush 49 because of the movement to the right of the core or armature of magnet D) brush 50, conductor 53, brush 46, pin 45 (which has returned to normal position in contact with the brush 46 because of the deenergization of the magnet C due to discontinuance of contact at 6) brush 47, conductor 54, brush 23, the lamp W being thus in a circuit in shunt with the winding 26 of the magnet D, the current 75 passing on through conductor 28 and signal wire 34 as previously described.

At station B the energization of the magnet E causes or allows the red semaphore to be displayed and the red light R at station 80 B burns. Thus, a car passing the trolley switch having the contact 6, causes the white light and the white semaphore to be displayed at station A and the red semaphore and red light to be displayed at station B. The signals remain in this condition until the car has passed over the section or block 85 1 and passes to the turnout at B when contact is made again by the trolley or the contact device between the conductor 5 and the switch contact 55 which then allows current to pass from conductor 5 through contact 55, conductor 56, through the winding 57 of the electro-magnet or solenoid F, thence through conductor 58, brush 59, contact ring 90 60, brush 61, conductor 62, resistance 63, conductor 19 to return conductor or earth 20. The contact rings 30 and 60 are carried by the movable member of the solenoid or magnet F and when that member is attracted 95 toward the right the ring 60 leaves brushes 59 and 61, thus breaking the short circuit of the resistance 64, causing that resistance then to be cut into the circuit of the magnet or solenoid winding 57. The current through 100 the winding 57 is thus reduced after the core or armature has been fully or partly attracted. This reduced current suffices to hold the core or armature in attracted position. Simultaneously, however, the contact 110 ring 30 is withdrawn from between the brushes 29 and 31 thus breaking the circuit through the signal wire 34, the winding 26 of the magnet D and through the white light W, both at station A, thus extinguishing 115 the white light W and allowing the spring to return the movable member of the solenoid or magnet D toward the left moving the white semaphore to invisible position and also stepping the wheel 21 back again to 120 normal position where the brush 23 rests upon the insulation 22, thus restoring all parts at station A to normal. The energization of the winding 57 of the magnet F at station B continues only while there is contact between the conductor 5 and the switch contact 55. The core or armature of the magnet or solenoid F returns then to normal position under the influence of a spring, 125 but returns very slowly due to the action of 130

a dash pot hereinafter described, this return movement being retarded so as to allow the actuation and movement of the mechanism at A to normal position before circuit is again established between the ring 30 and brushes 29 and 31 at station B.

Assuming that a car has passed from turnout A past the switch contact 6 onto the section 1, if another car follows it past the contact 6 into the section 1, current again flows from conductor 3 to contact 6 through conductor 7 and through the conductor 11 and the winding 12 of the magnet or solenoid C at station A. The preceding car, however, has caused the wheel 21 at station A to be stepped around one notch so that the magnet or solenoid D is energized and the white semaphore and white light are displayed. This second energization of the magnet or solenoid C, however, simply serves to step the wheel 21 around one more notch; but in doing so contact between brush 23 and wheel 21 continues and the contact between pin 45 and the brushes 46 and 47 is interrupted causing the white light W at station A to blink or to be temporarily extinguished until contact at 6 is broken and the armature or core of the magnet C at station A is returned to normal by a spring, reestablishing the circuit of the white light W at station A through the pin 45 and brushes 46 and 47. And the operation is the same for each successive car following into the block or section 1. And for each car passing out to the turnout at station B the contact is made at 55 interrupting the signal wire 34 at brushes 29 and 31 and ring 30 at station B thus causing a similar number of deenergizations of the magnet D at station A, thus stepping the wheel 21 back again a corresponding number of notches, the last car passing out returning it to normal position where the brush 23 rests upon the insulation 22. For traffic toward the left from turnout B to block 1 the contacts are made between the conductor 4 and the contact 6 at station B, thus causing the energization of magnet C at station B with the consequent energization of magnet D resulting in the display of the white semaphore and white light at station B and the energization of the magnet or solenoid E at station A with the consequent display of the red light and red semaphore at station A; and the action for a plurality of cars following each other into the block is the counting in and counting out action previously described.

It being the rule that a motorman shall not drive his car into the block or section 1 unless as his car passes the switch contact 6 he sees the white light appear, or in the case when one or more cars are already in the block 1 going in the same direction he sees the white light W at his turnout blink, when a car passes the contact 6 into the block

1, the magnet E at the distant station is energized, as heretofore described, displaying the red semaphore and the red light at the distant station. If, now, a motorman at that distant station attempts to run a car by that station into the section 1 in spite of the red semaphore and red light displayed against him, when contact is made at 6 at that station, no current can flow through the conductor 7 because the magnet E at that station has attracted its armature or core toward the left, thus causing the ring 9 to leave the brushes 8 and 10 and thus making it impossible to energize the magnet or solenoid C at that station to cause the display of his permissive white semaphore or white light. Whenever the magnet or solenoid E is energized, as described, it also causes the ring 41 to separate from brushes 42 and 40 thus inserting in the circuit of its winding 38 a resistance 65 to reduce the current flowing, which current is sufficient, nevertheless, to hold the parts in attracted position and to prevent excessive heating as in the case of the other magnet winding resistance described. This will prevent the destruction of the coil through overheating, should the motorman permit his car to remain for an indefinite time in such position as to close the circuit through the switch contact and the coil. And suppose a motorman drives his car past the contact 6 at a station and enters the block, but immediately backs off the block over the other track past contact 55. First the contact will be made at 6, resulting in the operations heretofore described in the display of the home white semaphore and white light and the distant red semaphore and red light, and later a contact occurs at 55 resulting in the energization of the home magnet or solenoid F thus breaking circuit at the ring 30 and brushes 29 and 31 in the signal wire 34 causing all the parts to again assume their normal non-displaying positions at both stations. As the signals are cleared or restored to normal by the temporary interruption of current in the signal conductor 34 at any point in it, it is evident that this may be caused at either station by opening any one of the four switches in series.

Should two cars approach the block or section 1 from opposite ends and one of them run under its switch contact 6 an instant before the other, the motorman on that car seeing the white signal appear would go ahead and the motorman at the other end of the block seeing the red signal appear but not being able to stop before passing his switch contact 6 would have to pass the switch contact 6 and back over it again to wait; in thus backing over the switch contact 6 the signals would not be affected because the red semaphore magnet E at that station is energized and has interrupted the

circuit of the magnet C at that station by the withdrawal of the ring 9 from the brushes 8 and 10.

Should two cars approach the block or section 1 from opposite ends and strike their respective switch contacts 6 at the same instant the permissive white signals would not be set at either station. This because the magnets C at both stations would be simultaneously energized causing the brush 23 and wheel 21 at both stations to come into contact so that the signal wire 34 would be connected at both ends to the trolley or contact conductor, so that no current would flow through the magnets D at either station, because of lack of difference in potential. Both cars would then back to or beyond their respective trolley switches and the first one arriving again at its trolley switch 6 would set the signals holding the other car and rendering the circuit controlled by the contact 6 at the station of the other car ineffective.

In the unusual case of a motorman setting the signals by passing the switch contact 6 and then immediately backing off over the same contact he can clear all the signals by opening the hand switch 33 at his station as many times as he has passed his switch 6, to return wheel 21 to normal, and then leaving it closed. But, as above described, in ordinary traffic, cars leaving the block will clear all the signals automatically because of the control exercised by the contacts 55.

By the arrangement here shown the burning out or failure of any of the electric lamps does not affect the operation of the signaling mechanism which continues to display the semaphores; and thus no false indication of safety can be produced by the burning out or failure of a lamp.

To provide for the case where the electric power of the railway system fails for any reason, thus causing a condition of very low or no voltage upon the power line, and yet assure that the signals will not have changed their condition upon return of power or voltage, I provide a no-voltage lock to hold the signal circuits during failure of power in the same condition they were in before failure of power. For this purpose I provide a no-voltage solenoid or magnet G whose winding 66 has one terminal joined by conductors 25' and 25 with the trolley wire or contact conductor, while its other terminal connects by conductor 67, through resistance 68 and conductor 69 with the earth or return conductor 20. So long, then, as power is upon the trolley or contact conductor of the system the magnet or solenoid G is energized and holds its armature or core in the attracted position, thus holding a lock member 70 from engaging in the notch 71 in the movable member of the magnet or solenoid D. However, when the volt-

age on the contact conductor or trolley wire falls to zero or nearly zero, the core or armature of the solenoid or magnet G is released allowing a spring to move the lock member 70 into the notch 71 to maintain the movable member of the solenoid or magnet D in the attracted position, thus maintaining the signal circuits in the condition they were in immediately before cessation of power or voltage. Incidentally this maintains the white semaphore displayed at the home station, but the white light at the home station and the red light and red semaphore at the distant station have returned to normal. But since the movable member of the magnet or solenoid D is maintained in the attracted or signal displaying position, immediately upon return of power or voltage the home white light again glows and the distant red light and red semaphore are immediately again displayed. In other words, by this arrangement failure of power or voltage upon the supply conductors or on the contact or trolley conductor will not return the signal circuits to normal or to any other condition than that they were in at the moment of failure of power or voltage.

Coming now to a consideration of one of the forms the signal operating or controlling mechanism may take, reference is to be had to Figs. 2 to 6 inclusive. Referring to Fig. 2, the magnets or solenoids C, D, E, and F, are shown in longitudinal vertical section. The housings or jackets 72 of the magnets C and D are provided with ears or lugs 73 by which they are secured to the under side of a wooden board or plate of insulating material 74 which, in turn, is secured by bolts 75 to the cast iron or other suitable casing 76. Upon the board or plate 74 are mounted a plurality of binding posts 77 extending above and below the plate 74, the lower terminals being adapted to receive the connecting wires from the various magnets and contacts below, while the upper terminals are adapted to press against and contact with opposed contact springs 78 secured to the insulating board or plate 79 supported by internal ears 80 on the casing 76, such springs being connected with corresponding binding posts 81 upon the top of the plate or board 79, to these binding posts 81 being led the outside conductors and connections, the case 76 being suitably secured upon any post or pole or other support along the line of the railway and visible to the motorman. And the housings or jackets 72 of the magnets E and F are tied by the members 82 and are secured, as by screws, to the under sides of the jackets or housings 72 of the magnets C and D. Thus the housings of the magnets C and D are tied together by the ties 82 cast integral with them and the housings of the magnets E and F are similarly tied and the four magnets form a mechanical

unit which is supported from the under side of the plate 74.

The magnet C has the movable core or armature 83 which, upon the energization of the magnet C, is attracted toward the right, in opposition to the spring 84, being guided through the core member 85 by the rod 86 which on its right end carries a jaw member 87 which abuts endwise against a similar jaw member 88 carried by the core or armature 89 of the magnet D, the latter being guided in its movements by the rod 90 acted upon by the spring 91 which tends to hold the core or armature 89 toward the left, as viewed in Fig. 2. Between the jaws of the member 87 is pivoted at 92 a pawl 93, under the control of the spring 94 and adapted to engage the ratchet wheel 95. Between the members of the jaw 88 is pivoted a similar pawl 96 also adapted to engage the ratchet wheel 95.

Upon the energization of the magnet C its core or armature 83 is attracted toward the right causing the pawl 93 to engage the ratchet wheel 95 and rotate it the space of one notch. Such movement of the core 83, however, is accompanied by a pushing over of the core 89 of the magnet D against the opposition of the spring 91. Upon deenergization of the magnet C the spring 84 returns the core 83 to the left, as viewed in Fig. 2, and upon the deenergization of the magnet D the spring 91 pushes the core 89 toward the left causing the pawl 96 to engage the ratchet wheel 95 to step it in opposite direction the space of one notch.

At the left end of the core or armature 83 of the magnet C is carried the contact pin 15, insulated from the core 83, with which engage the brushes or contacts 14 and 16, 14 only appearing in Fig. 2, 16 being directly behind the same, such brushes or contacts being supported by the block of insulating material 97 supported upon the head 98 of the magnet C. And approximate the right hand end of the jaw member 87 is disposed the contact pin 45, insulated from such jaw member 87, and engaged upon the front by the contact or brush 46 and on the rear by the brush or contact 47. To the left end of the jaw member 88 is carried the contact pin 48, insulated from the member 88, and adapted, upon the movement of the core member 89 toward the right, to come between and engage the brushes 49 and 50, 49 in front and 50 in the rear, these brushes 46, 47, 49 and 50 being supported upon the block of insulating material 99 carried by the tie 82.

On the head 100 of the magnet D is a plate 101 through a perforation in which extends the rod 90 carrying the transversely extending pin 102 disposed between the ears 103, and to the right of them, upon the bell 104 having the crank arm 105 to

which is pivoted the arm 106 extending upwardly through the plate 74 and the plate 79 to engage the under side of the counter weight 107 upon the rod or arm 108 pivoted at 109 and carrying at its outer end the white semaphore disk 110.

The movable core or armature 111 of the magnet E is adapted to be attracted toward the left; as viewed in Fig. 2, in opposition to the spring 112 acting upon the rod 113 which, similarly to the rod 90, carries at its outer end a transversely extending pin adapted to engage with the wings 103, of the bell crank lever 104 having the crank arm 105 on which is pivoted the upwardly extending rod 106 which passes through the plates 74 and 79 and engages the under side of the counter weight 107 upon the rod 114 pivoted at 115, the rod 114 carrying at its outer end the red semaphore 116. On the right of the core or armature 111 is supported the rod of fiber or other insulating material 117 which carries the contact rings 9 and 41 adapted to engage respectively the brushes or contacts 8 and 10 and 42 and 40, 90 10 and 40 being in front and 8 and 42 in the rear, these brushes being supported by the insulating member 99. By the core or armature 118, of the magnet F, is carried a rod of fiber or other insulating material 119 carrying the contact rings 30 and 60 with which engage respectively the pairs of brushes or contacts 29 and 31 and 59 and 61, 29 and 59 being shown in front while 31 and 61 are in the rear, these brushes also being supported by the insulating member 99.

When the magnet F is energized the core 118 is attracted to the right, as viewed in Fig. 2, and guided by the rod 120 which passes through the hollow core member 121 forming part of the head 122. Carried by the rod 120 and fitting within the bore of the core member 121 is the dash pot piston 123 having a small hole forming a small 110 communicating passage between the chambers to the right and to the left of the piston 123. In the chamber to the left of the piston 123 is a valve 125 surrounding the rod 120 and pressing against the inner wall of the core member 121 under the influence of the spring 126, the opening through the core member 121 around the rod 120 being considerably larger than said rod. When the core member 118 is attracted toward the right it carries the piston 123 toward the right end of the chamber and the valve 125 leaves its seat and permits oil to enter into the chamber to the left of the piston 123. When the magnet F is deenergized the 120 spring 124 presses the parts toward the left and the valve 125 comes up to its seat trapping the oil in the chamber to the left, the only escape for the oil being the slow and retarded one through the hole in the piston 130

123, thus retarding the movement of the parts toward their normal position for the purpose hereinbefore described.

The tank 127, of cast iron or other suitable material, surrounds the magnets C, D, E, F, and G, the resistances hereinbefore mentioned, and other apparatus and is supported to the upper casing 76 by suitable bolts 128, gaskets or seals 129 intervening. Within the tank 127 is contained suitable insulating oil rising to a level above the magnets and all moving contacts as, for example, to a level indicated by the line X—X. This oil is admitted within the magnet housings and is the oil which serves for dash pot purposes in connection with magnet F.

In the front of the casing 76 are three circular openings 131, 132 and 133. Through the upper opening 131 are visible the white or red semaphores 110 and 116. Back of the opening 132 is disposed the white electric light W and behind the opening 133 is disposed the red light R.

When the magnet D is energized the rod 90 carries the pin 102 to the right out of the way of the wings 103 upon the bell crank lever 104 allowing the counter weight 107 to descend and thereby lift the white semaphore 110 to the dotted line position at the opening 131 as seen in Fig. 2. Upon the de-energization of the magnet D the spring 91 presses the rod 90 toward the left causing the pin 102 to engage the bell crank lever 104, thus raising the rod 106, and raising the counter weight 107 causing the white semaphore 110 to return to the full line position shown in Fig. 2. By this construction, the semaphore is lifted to indicating position by the counter weight; and thus the parts are relieved of any blows or too sudden actuation which might otherwise result from the energization of the magnet D.

When the magnet E is energized the core member 111 is attracted toward the left in opposition to spring 112 causing the transverse pin upon the rod 113 to be moved out of the way of the wings 103 of the bell crank lever 104, thus allowing the counter weight 107 upon the rod 114 to raise the red semaphore 116 up to the opening 131 to be visible through such opening. Upon de-energization of the magnet E the spring 112 causes the pin on the rod 113 to engage the wings on the bell crank lever 104 to raise the rod 106 and the counter weight 107 and returning the semaphore 116 to the full line position shown in Fig. 2.

The white semaphore 110, when in full line position as shown in Fig. 2, intervenes between the white light W and the opening 132; and similarly, the semaphore 116 intervenes between the red light R and the opening 133, so that when either semaphore is in normal position it prevents any light com-

ing through the opening intended for either 65 of the electric lights.

Lenses may be applied to the openings 132 and 133, a white lens for the white light W and a red lens for the lamp R, which may be, in fact, an ordinary clear globe incandescent lamp, the red color being imparted by the lens. By this arrangement of semaphores, lights, and openings, it is apparent that a single opening serves for the display of both semaphores and that only three openings are necessary for the display of two lights and two semaphores, the semaphores being symmetrically disposed so that either one or the other may be displayed at the semaphore opening. 80

Referring to Figs. 3, 4 and 5 the no-voltage magnet G is shown attached to the housing of the magnet D which is here shown in end elevation, the magnet G being shown principally in vertical section. When the 85 magnet G is energized, which it is so long as sufficient voltage is upon the line, its core member 134 is held in the upward and attracted position, the rod 135 carried thereby holding the rod 136 rotated about its pivot 90 137 against the spring 138, thus holding its half circular locking end 70 away from the notched rod 90 of the magnet D. Should the power or voltage on the line fail when the magnet D is energized, the core member 95 134 drops by gravity, the drop being limited by a cross pin 139, thus allowing the spring 138 to raise the rod 136 to bring its half circular locking end 70 into the notch 71 of the rod 90. This prevents the spring 91 100 from returning the movable member of the magnet D to the left and normal position with the effect hereinbefore described.

In Fig. 6, the pivot pin or stud 140, secured to the lug 141 upon the tie 82 between 105 the housings of magnets C and D, has mounted thereon the rotatable fiber or other insulating hub 142. To this hub 142 is secured the ratchet wheel 95 with which engage the pawls 93 and 96, as hereinbefore described. 110 Carried by the hub 142 and therefore actuated by the wheel 95, is the metallic contact wheel 21 with which continuously engages the brush 24, and which carries the contact pin 35 and the insulation section 22. The 115 brushes 23, 24 and 36 are mounted upon the block of insulating material 143 supported within the tank 127.

While the conductors 1, 2, 3, 4 and 5 are here referred to as a trolley wire or conductor, such as commonly suspended overhead for the traveling contact of an electric railway car or train, it is to be understood that my invention is equally applicable to third rail systems or conduit systems where the 125 contact conductor is below ground.

What I claim is:

1. In a signaling system, the combination

with a switch contact, of electro-magnetic means controlled by said contact, a step by step mechanism actuated by said electro-magnetic means, a semaphore, and a semaphore controlling magnet having a movable member, said movable member being actuated by said electro-magnetic means when said step by step mechanism is actuated.

2. The combination with a switch contact, 10 of electro-magnetic means controlled thereby, step by step mechanism actuated by said electro-magnetic means, a semaphore, and a semaphore controlling magnet having a movable member, said movable member being 15 actuated by said electro-magnetic means when said step by step mechanism is actuated, said step by step mechanism when actuated closing the circuit of the winding of said semaphore controlling magnet, whereby 20 its movable member is retained in position after actuation by said electro-magnetic means.

3. The combination with a switch contact, 25 of a vehicle for bringing said contact momentarily into circuit, electro-magnetic means controlled by said contact, a semaphore, a semaphore controlling magnet having a movable member, said electro-magnetic means actuating said movable member, 30 and means for energizing said magnet after the movable member has been actuated.

4. The combination with a switch contact, 35 of electro-magnetic means controlled thereby, a semaphore, a semaphore controlling magnet having a movable member actuated by said electro-magnetic means, means causing the energization of the winding of said semaphore controlling magnet after such actuation, and an electric light signal to be 40 displayed simultaneously with the semaphore controlled by said magnet, the circuit of said light being interrupted at one point upon the energization of said electro-magnetic means and closed at another point by 45 the operation of the movable member of said semaphore controlling magnet, and finally closed at the first point by the return of said electro-magnetic means to normal position.

5. The combination with a switch contact, 50 of electro-magnetic means controlled thereby upon the passage of each car or train past said switch contact, a step by step mechanism operated one step for each energization of said electro-magnetic means, a semaphore, a semaphore magnet the circuit of whose winding is closed by the first step movement of said step by step mechanism, a switch contact at a distant station controlling 55 said semaphore magnet at the home station, and means controlled by said semaphore magnet for actuating said step by step mechanism in reverse direction one step for each car or train passing said distant switch

contact, the last car or train causing the return of said step by step mechanism and said semaphore magnet to normal. 65

6. In an electric signaling system, the combination with a vehicle controlled contact, 70 of electro-magnetic means at a home station controlled by said contact, said electro-magnetic means having a movable member, means for returning said movable member to normal position immediately upon de-energization of said electro-magnetic means, 75 permissive and danger signals at said home station, a controlling magnet for each of said signals, and switching mechanism preventing simultaneous energization of said magnets, said movable member being disconnected from said switch and the armature of said permissive signal controlling magnet but adapted to actuate both the same. 80

7. In an electric signaling system, the combination with a vehicle controlled contact at a home station, 85 of an electro-magnet at said home station controlled by said contact, step-by-step mechanism at the same station controlled by said electro-magnet, a signal, a signal controlling electro-magnet 90 at said home station, a second signal at said home station, switching mechanism controlling said signal controlling electro-magnet and said second signal, said switching mechanism when actuated preventing control of 95 said second signal and allowing control of said signal controlling magnet, said switching mechanism actuated simultaneously with said step-by-step mechanism, a vehicle controlled switch contact at a distant station, 100 and an electro-magnet at said distant station controlled by said contact, said electro-magnet at said distant station when energized interrupting the circuit of said signal controlling magnet at said home station. 105

8. In a signaling system, the combination with a switch contact, of electro-magnetic means controlled by said contact, a semaphore, a semaphore controlling magnet having a movable member, and a step-by-step mechanism, 110 said step-by-step mechanism and said movable member of said semaphore magnet being simultaneously actuated by said electro-magnetic means.

9. In a signaling system, the combination with a switch contact, of electro-magnetic means controlled by said contact, a semaphore, a semaphore controlling magnet having a movable member, a step-by-step mechanism, 115 said step-by-step mechanism and said movable member of said semaphore magnet being simultaneously actuated by said electro-magnetic means, and means controlled by said step-by-step mechanism for energizing 120 said semaphore magnet after such actuation.

10. In a signaling system, the combination with a switch contact, of electro-mag-

netic means controlled by said contact, a semaphore, a semaphore controlling magnet having a movable member, a step-by-step mechanism, said step-by-step mechanism and said movable member of said semaphore magnet being simultaneously actuated by said electro-magnetic means, and means controlled by said step-by-step mechanism for energizing said semaphore magnet after such actuation, said step-by-step mechanism being actuated in reverse direction by said movable member when said semaphore magnet is deenergized.

11. The combination with a vehicle controlled home switch contact, of electro-magnetic means temporarily controlled thereby at the same home station, said electro-magnetic means having a movable member, a switch, said switch being disconnected from said movable member but adapted to be operated thereby, a semaphore, a semaphore controlling magnet at the home station whose armature is actuated by said electro-magnetic means, said semaphore controlling magnet controlled by said switch, a vehicle controlled switch contact at a distant station, and a magnet winding at said distant station controlled thereby, said magnet winding when energized interrupting the circuit of said semaphore controlling magnet at the home station.

12. The combination with a vehicle controlled home switch contact, of electro-magnetic means controlled thereby at the same home station, step-by-step mechanism and a switch at said station controlled by said electro-magnetic means, a semaphore controlling magnet at said home station controlled by said switch, means responsive to deenergization of said semaphore controlling magnet for reversely moving said step-by-step mechanism, a vehicle controlled switch contact at a distant station, and a magnet winding controlled thereby, said magnet winding when energized interrupting the circuit of said semaphore controlling magnet at said home station, whereby said step-by-step mechanism is reversely moved.

13. The combination with a vehicle controlled switch contact, of electro-magnetic means controlled thereby at the same home station, a semaphore, a semaphore controlling magnet having a movable member, a step-by-step mechanism, said step-by-step mechanism and said movable member being simultaneously actuated by said electro-magnetic means, means for returning said movable member, a vehicle controlled switch contact at a distant station, a magnet controlled thereby, said magnet when energized interrupting the circuit of said semaphore magnet at the home station, whereby said semaphore is released so as to return to normal, said step-by-step mechanism being actuated

in reverse direction by said movable member when the latter is released. 65

14. The combination with a vehicle controlled switch contact, of electro-magnetic means controlled thereby, a semaphore, a semaphore magnet having a movable member, a circuit controller, said circuit controller and said movable member being simultaneously actuated by said electro-magnetic means, whereby said semaphore is moved and said circuit controller causes the energization of 75 said semaphore magnet, and means associated with said movable member for controlling the circuit of a signal light.

15. In a signaling system, the combination with a vehicle controlled switch contact, of 80 electro-magnetic means controlled by said contact, a home semaphore, a controlling magnet therefor, step-by-step mechanism, said step-by-step mechanism and said home semaphore being simultaneously actuated by 85 said electro-magnetic means, a semaphore at a distant station, an operating magnet therefor, said magnet and the home semaphore magnet being simultaneously energized.

16. In a signaling system, the combination 90 with a vehicle controlled switch contact, of electro-magnetic means controlled by said contact, a home semaphore, a controlling magnet therefor having a movable member, said movable member being actuated by said 95 electro-magnetic means, a semaphore at a distant station, a controlling magnet therefor, said semaphore magnets at both stations being simultaneously energized.

17. In a signaling system, the combination 100 with a vehicle controlled switch contact, of electro-magnetic means controlled by said contact, a home semaphore, a controlling magnet therefor having a movable member, said movable member being actuated by said 105 electro-magnetic means, means causing energization of said semaphore magnet after said actuation, a semaphore at a distant station, an operating magnet therefor, said semaphore magnets at both stations being 110 simultaneously energized.

18. In a signaling system, signaling apparatus comprising at each station electro-magnetic means temporarily energized upon the passage of each vehicle, a signal, a circuit 115 therefor, a plurality of switches in series in said signal circuit, an electro-magnet, a switch causing the energization of said electro-magnet upon the first energization of said electro-magnetic means, one of the 120 switches in said signal circuit held closed by said electro-magnet, and another of said switches in said signal circuit opened upon each energization of said electro-magnetic means.

19. In a signaling system, signaling apparatus comprising at each station a lamp circuit, a plurality of switches in series in said

lamp circuit, electro-magnetic means energized upon the passage of each vehicle, one of said switches opened upon each energization of said electro-magnetic means, an electro-magnet, and means controlled by said electro-magnet for holding another of said switches closed after the passage of the first vehicle.

20. In a signaling system, the combination with a vehicle controlled contact, of electro-magnetic means controlled by said contact, a semaphore at a home station, a controlling magnet for said semaphore, step-by-step mechanism, said step-by-step mechanism and 15 said home semaphore being simultaneously actuated by said electro-magnetic means, a semaphore at a distant station, a controlling magnet for said distant semaphore, means governed by said step by step mechanism 20 for simultaneously energizing said home and distant semaphore controlling magnets, a home signal at said distant station, and means controlled by said distant semaphore controlling magnet preventing the display 25 of the home signal at said distant station.

21. In a signaling system, the combination with a vehicle controlled switch contact, of electro-magnetic means controlled by said contact, a semaphore at a home station, a 30 controlling magnet for said semaphore having a movable member, said movable member being actuated by said electro-magnetic means, a semaphore at a distant station, a controlling magnet for said distant semaphore 35 30, means governed by said electromagnetic means for simultaneously energizing said semaphore magnets at both stations, a home signal at said distant station, and means controlled by said distant semaphore 40 controlling magnet for preventing the display of said home signal at said distant station.

22. In a signaling system, the combination with a single conductor extending between 45 signal stations, a switch at each station associated with said single conductor and controlling a plurality of branches, a permissive signal magnet at each station, one branch of each switch being connected to 50 one terminal of a power circuit through said permissive signal magnet, a stop signal magnet at each station, another branch of each switch being connected to the other terminal of said power circuit through said stop signal 55 magnet, a vehicle controlled contact at a home station, electro-magnetic means at said home station controlled by said contact and having a movable member, said movable member being disconnected from but adapted 60 to actuate said switch from one position to another, means restoring said switch to preceding position in response to deenergization of said permissive signal magnet, and a magnet at a distant station for interrupt-

ing the circuit of said permissive signal 65 magnet.

23. In a signaling system, the combination with a single conductor extending between signal stations, of a switch at each station associated with said single conductor and 70 controlling a plurality of branches, a permissive signal magnet and a stop signal magnet at each station, one branch of each switch being connected to one terminal of a power circuit through said permissive signal 75 magnet, another branch of said switch being connected to the other terminal of said power circuit through said stop signal magnet, a vehicle controlled electro-magnet at a home station having a movable member, said movable member being disconnected from but adapted to actuate said switch from one position to another, said permissive signal magnet having a movable member, said movable member of said permissive signal magnet restoring said switch to preceding position upon deenergization of said permissive signal magnet, an electro-magnet at a distant station for interrupting the circuit of said permissive signal magnet, and means 80 controlled by said stop signal magnet for interrupting the circuit of said switch actuating magnet.

24. In a signaling system, a trolley switch contact, an electro-magnet controlled thereby, a semaphore, a semaphore controlling magnet, a switch controlling the same, the movable member of said electro-magnet actuating said switch and the movable member of said semaphore magnet, a signal circuit, switches in series in said signal circuit, one of said switches opened upon each energization of said electro-magnet, and another of said switches maintained closed by said 95 semaphore magnet.

25. In a signaling system, a trolley switch contact, an electro-magnet controlled thereby, a semaphore, a semaphore controlling magnet, a switch controlling the same, the movable member of said electro-magnet actuating said switch and the movable member of said semaphore magnet, a lamp signal circuit, switches in series in said lamp signal circuit, one of said switches opened upon each energization of said electro-magnet, and another of said switches maintained closed by said 100 semaphore magnet.

26. In a signaling system, an electro-magnet energized upon the passage of each vehicle, a second electro-magnet, a switch 115 controlling said second magnet, said first electro-magnet when first energized closing said switch and actuating the movable member of said second magnet, a signal circuit, a plurality of switches in series in said circuit, one of said switches opened upon each energization of said first electro-magnet, another of said switches held closed by said 120 125

second magnet, step-by-step mechanism controlling said first named switch actuated a step for each energization of said first electro-magnet, and means associated with 5 said second electro-magnet for returning said step-by-step mechanism toward normal a step for each deenergization of said second magnet.

27. In a signaling system, signaling apparatus comprising means for closing a signal circuit at one or more points upon the passage of the first vehicle and for temporarily opening said circuit at another point upon the passage of the first and each succeeding vehicle, electro-magnetic means for maintaining said signal circuit closed at one of the first named points, the circuit of said electro-magnetic means being closed by the first named means, said electro-magnetic 20 means remaining energized after the passage of the first vehicle, and means responsive to failure of energy in the system for maintaining said signaling apparatus at the condition of indication at the time of failure of energy.

28. In a signaling system, signaling apparatus comprising means for closing a signal circuit at one or more points upon the passage of the first vehicle and for temporarily 30 opening said circuit at another point upon the passage of the first and each succeeding vehicle, electro-magnetic means for maintaining said signal circuit closed at one of the first named points, the circuit of said electro-magnetic means being closed by the first named means, and said electro-magnetic 35 means remaining energized after the passage of the first vehicle, and means responsive to failure of energy in said system for insuring said signaling apparatus giving the same indication upon return of energy as at the time of failure of energy in 40 said system.

29. In a signaling system, the combination 45 with a switch contact, of electro-magnetic means controlled by said contact, a semaphore, a semaphore controlling magnet having a movable member, step-by-step mechanism, said step-by-step mechanism 50 and said movable member of said semaphore controlling magnet being simultaneously actuated by said electro-magnetic means, and means responsive to failure of energy in said system for insuring said semaphore 55 giving the same indication upon return of energy as at the time of failure of energy in said system.

30. In an electrical railway-signaling system, a vehicle controlled switch contact, electro-magnetic means, said electro-magnetic 60 means having a movable member, a signal circuit, means coöperating with the movable member of said electro-magnetic means maintaining said signal circuit closed after

the passage of the first vehicle, means controlled by said switch contact for temporarily interrupting said signal circuit upon the passage of each succeeding vehicle, and means responsive to failure of energy in 65 said system for locking said movable member in the position in which it maintains signal circuit closed.

31. In an electrical railway signaling system, a vehicle controlled switch contact, step-by-step mechanism controlled by said contact, said step-by-step mechanism being moved a step for each vehicle passing said contact, a signal, electro-magnetic means for controlling said signal, said electro-magnetic means having a movable member, said 70 step-by-step mechanism controlling said electro-magnetic means, said movable member actuating said step-by-step mechanism to return the same to normal, and means 75 responsive to failure of energy in said system for locking said movable member of said electro-magnetic means.

32. In an electric railway signaling system, the combination with a vehicle controlled switch contact, of a signal, step-by-step mechanism controlled as to movement in one direction by said contact for controlling said signal, a member for actuating said step-by-step mechanism in reverse direction, means for locking said member, and 80 means withholding said locking member during the presence of energy on said system.

33. In an electric signaling system, a block, signal apparatus at each end of said block, a single conductor extending between 85 said apparatus and connecting the same, each of said apparatus comprising a vehicle controlled switch contact, an electro-magnet controlled by said contact, step-by-step mechanism, controlled by said electro-magnet, permissive and stop signals, switching mechanism actuated simultaneously with 90 said step-by-step mechanism, said switching mechanism when actuated controlling said permissive signal and preventing control of 95 said stop signal.

34. In an electric signaling system, the combination with a vehicle controlled contact, of electro-magnetic means at the same home station controlled thereby, said electro-magnetic means having a movable member, means for returning said movable member to normal position immediately upon deenergization of said electro-magnetic means, permissive and danger signals at 100 said home station, a danger signal at a distant station displayed simultaneously with the permissive signal at said home station, controlling magnets for said signals, switching mechanism at said home station preventing simultaneous energization of said signal controlling magnets, said switching mechanism disconnected from but adapted 105

to be actuated by said movable member in one direction only, and the armature of said permissive signal magnet adapted upon de-energization thereof to actuate said switch-
5 ing mechanism in reverse direction.

35. In a signaling system, signaling apparatus comprising a signal, step-by-step mechanism, a plurality of solenoids and their cores associated with said step-by-step mechanism, the solenoid cores being disconnected from but adapted to actuate said step-by-step mechanism, a vehicle controlled contact controlling one of said solenoids, and another of said solenoids controlling
10 said signal, the energization of said contact controlled solenoid actuating the core of said signal controlling solenoid.

36. In a signaling system, signaling apparatus comprising a signal, step-by-step mechanism, a pair of solenoids and their cores disposed on opposite sides of said step-by-step mechanism, said solenoid cores being disconnected from but adapted to actuate said step-by-step mechanism, means for re-
20 turning said solenoid cores to their unat-
tracted positions, a vehicle controlled switch contact controlling one of said solenoids, said step-by-step mechanism controlling the other of said solenoids, and said signal con-
25 trolled by said last mentioned solenoid, the energization of said contact controlled sole-
noid actuating said step-by-step mechanism and the core of said signal controlling sole-
noid.

35 37. In a signaling system, signaling apparatus comprising at the same station per-
missive and stop signals, a pair of solenoids having movable cores, a vehicle controlled switch contact controlling one of said sole-
noids, the core of the other solenoid actuated
40 by the core of said first mentioned solenoid, said permissive signal controlled by the core of said second solenoid, a third solenoid con-
trolling said stop signal, and a switch on the
45 movable core member of said third solenoid controlling a circuit of said first mentioned solenoid.

38. In a signaling system, signaling ap-
paratus comprising at the same station per-
50 missive and stop signals, a pair of solenoids having movable cores, a vehicle controlled switch contact controlling one of said sole-
noids, the core of the other solenoid actuated by the core of said first mentioned solenoid,
55 said permissive signal controlled by the core of said second solenoid, a third sole-
noid controlling said stop signal, a switch on the movable core member of said third sole-
noid controlling a circuit of said first
60 mentioned solenoid, a second vehicle con-
trolled switch contact, and a fourth solenoid controlled thereby, and a switch upon the movable core member of said fourth sole-
noid controlling said second solenoid.

39. In a signaling system, signaling ap- 65 paratus comprising at the same station per-
missive and stop signals, a pair of solenoids having movable cores, a vehicle controlled switch contact controlling one of said sole-
noids, the core of the other solenoid actu-
70 ated by the core of said first mentioned sole-
noid, said permissive signal controlled by the core of said second solenoid, a third sole-
noid controlling said stop signal, a switch on the movable core member of said third sole-
noid controlling a circuit of said first
75 mentioned solenoid, a second vehicle con-
trolled switch contact, a fourth solenoid con-
trolled thereby, and a switch upon the movable core member of said fourth sole-
noid controlling said second solenoid, said first
80 and second solenoids disposed as an unit in
alinement with each other, and said third
and fourth solenoids supported upon said
unit comprising said first and second sole-
85 noids.

40. In a signaling system, signaling appa-
ratus comprising a signal, step-by-step
mechanism, a pair of solenoids having their
cores independent and disposed in aline-
90 ment with each other and extending on op-
posite sides of said step-by-step mechanism,
said step-by-step mechanism actuated in one
direction by the core of one of said solenoids
and in the other direction by the core of the
95 other of said solenoids, a vehicle controlled
switch contact controlling one of said sole-
noids, and said signal controlled by the
other of said solenoids, the core of said sig-
nal controlling solenoid adapted to be en-
gaged and actuated by the core of said con-
tact controlled solenoid.

41. The combination with a vehicle con-
trolled switch contact, of a light signal, a
circuit therefor, switches in said circuit, an
105 electro-magnet closing one of said switches
upon the passage of the first vehicle past
said switch contact, a second electro-magnet
holding said switch closed, and another of
said switches temporarily opened by said
110 first mentioned electro-magnet upon the pas-
sage of each succeeding vehicle.

42. In a signaling system, signaling appa-
ratus at each station, a single signal con-
ductor extending between stations, means con-
trolling said signaling apparatus comprising
115 a branched signal circuit including said sin-
gle signal conductor, switches in said cir-
cuit, a magnet energized upon the passage
of the first vehicle for closing said signal
120 circuit, and temporarily energized upon the
passage of each succeeding vehicle for tem-
porarily interrupting a branch of said sig-
nal circuit.

43. In a signaling system, signaling ap-
paratus at each station, a single signal con-
ductor extending between stations, means
controlling said signaling apparatus com-

prising a branched signal circuit including said single signal conductor, switches in said circuit, a magnet energized upon the passage of the first vehicle for closing said 5 signal circuit, a second electro-magnet and means maintaining the same energized after the passage of the first vehicle for holding one of said signal circuit switches closed, and means controlled by said first-named 10 magnet for temporarily interrupting a

branch of said signal circuit upon the passage of each succeeding vehicle.

In testimony whereof I have hereunto affixed my signature in the presence of the two subscribing witnesses.

CARL P. NACHOD.
